CLAIM

The ornamental design for a tire for an automobile, as shown and described.

DESCRIPTION

FIG. 1 is a side perspective view of a tire for an automobile showing my new design, it being understood that the tread pattern is repeated throughout the circumference of the tire tread, the opposite side being the same as that shown; FIG. 2 is a front elevation view thereof, the opposite side being identical thereto;

FIG. 3 is a side elevation view of the right side; and,

FIG. 4 is a side elevation view of the left side.

In the drawings, the broken lines showing portions of the sidewall and inner bead depict portion of the tire that form no part of the claimed design.
